Des. 915

James R. Hyde, of Troy, N. Y.
Letters Patent No. 915. Dated July 14, 1857.

The schedule referred to in these Letters Patent, and making part of the same.

To all whom it may concern:

Be it known that I, James R. Hyde, of Troy,

Dec. 9/5

in the County of Rensselaer, and State of New York, have invented or produced a new and original design called "The Capitol" for plates or castings of cooking stoves; and I do hereby declare that the following is a full and exact description of the same, reference being had to the annexed drawings making a part of this specification, in which,

Fig: 1. is an elevation of the front plate, with a fire door;

Figure, 2, of a side plate, with an oven door; and

Figure, 3, of a foot.

My design for the front plate consists of the edge moulding A, the ornamental moulding B, and the enclosed swelling ground C, of fire check-work, with furrowed bars C; and that for the fire doors consists of the central ornament D, backed by the lace-work E, and enclosed by the border moulding F.

My design for the side-plates consists of the panel formed of the moulding F, and cap G, as a border to the check-work H, with the center ornament I, (which panel also forms the design for the feed door of the stove); the ash-cup ornamented by the check-work square K, the furrow L, and the acorn drop J; the series of drops M, along the projecting top of the plate; the moulding N, at the bottom; and the edge moulding A. That for the oven doors consists of the large central ornament, (composed of clusters of grapes, a, leaves, b, and vines, c, surmounting and winding about the vase, and tables in drapery, g,) backed by the lace-work E, and surrounded by the border moulding F.

My ornamental design for the foot consists of the compound ornament O, arranged upon the swelling upper part; and the leaflet P, at the bottom.

Having thus described my production, what I claim as new and desire to secure by letters patent, is, the ornamental design and configuration of the several plates or castings of a cooking stove herein described and fully represented in the annexed drawings.
